UNITED STATES PATENT OFFICE.

FRIEDRICH WALTER KRAUSE, OF ALTONA, GERMANY, ASSIGNOR TO JOHN FERREOL MONNOT, OF MILL HILL, LONDON, ENGLAND.

WALL PLUG.

Application filed December 29, 1924. Serial No. 758,557.

To all whom it may concern:

Be it known that I, FRIEDRICH WALTER KRAUSE, a German citizen, residing at Altona, Germany, have invented certain 5 new and useful Improvements in or Relating to Wall Plugs, of which the following is a specification.

This invention relates to wall plugs of the 10 type in which there is employed a fibrous or other material of a yielding or flexible nature which is easily subject to compression and expansion.

It is known that for the purpose of inserting plugs or forming a suitable support, 15 loose fibrous material, for instance cotton wool, is packed into the hole in the wall. It has been attempted to reduce the difficulties involved in such packing by forming the loose fibrous material into lightly glued, 20 yielding or braided sockets, but although these fibrous material sockets are more easy to insert than loose fibrous material, their holding power is smaller and less reliable.

When using loose fibrous material it is 25 forced into the hole in the wall until it is full. The fibrous material sockets have on the other hand the disadvantage that, owing to their lack of strength, they cannot be 30 forcibly driven into the hole in the wall, but only introduced into it with a slight clearance. Consequently the quantity of fibrous material introduced when using them is less than when loose fibrous material is used.

When a socket is used it grips only by the 35 radial spreading out of the socket which occurs when it is driven in by the screw or the like. The amount of such spreading out always depends therefore on the diameter of the screw or nail. If the hole in the wall 40 is even a trifle larger than the minimum diameter required to enable the socket to be introduced, the holding power of the socket will soon disappear.

In order to overcome the disadvantages 45 above referred to there is employed in accordance with the present invention a wall plug comprising a filling material of the kind hereinafter referred to, such as a soft fibrous substance or the like, held between 50 and stiffened by bars, wires, or the like connected together by a transverse portion at one end so as to form a stem-hold for the filling material and open at the other end, the bars or wires being provided with retaining means such as fingers and/or a hold-

ing collar, whereby the plug can be forcibly driven into a small hole in a wall or other member, the fibrous material of the plug being at the same time compressed, before the screw or nail to be inserted is driven in. By 60 this means a maximum quantity of fibrous material can be stiffened and held together without prejudicially affecting the degree of resiliency necessary for the material.

For the filling mass, there must be used a 65 material such as a fibrous material, for example cellulose or asbestos, which can be compressed from a long thin cylinder to a short and thick one accompanied by a yielding in the axial direction and expansion in 70 the radial direction, and which will penetrate flexibly and adapt itself to any shape of hole and fill up all the corners of the rough holes in the wall, and which when the compression continues, develops a uniformly 75 distributed, elastically increasing, exceedingly powerful pressure, and remains under pressure and properly transmits this frictional pressure between the nail or the like and the walls of the hole. 80

The necessary property that must be possessed by the filling material, namely that its density must be capable of being increased by pressure and that it must maintain the degree of increased density under 85 pressure, cannot be obtained by the use of soft metals or alloys for example.

By impregnating the fibrous material or the like such as cellulose with any of the usual preservatives, its life can be made 90 equal to that of wood, whilst by using asbestos, it can be rendered indestructible by heat.

A wall plug constructed in accordance 95 with the present invention can be easily and quickly introduced into a hole in a wall, and in consequence of the increased quantity of fibrous material available, affords a much more efficient grip and therefore holding power than a fibrous material socket loosely 100 introduced into the same hole. Even if the fibrous material stiffened in the manner above mentioned were introduced with the same clearance as the socket, it would still have a greater holding power than the latter, as owing to the use of the stiffening bars, the space between which is wholly filled with the fibrous material in place of a socket, there is available material for filling 105 the hollow space between the plug, and the 110

wall of the hole. In this way, larger variations in the admissible diameter of the hole become permissible, the safety and reliability of the plugs are accordingly increased, 5 and, owing to the distribution of the pressures in the body of fibrous material which is clamped by the stiffening bars, the soft front plaster portions of the walls are relieved from strain, so that breaking off of 10 such portions is avoided.

It is immaterial for their action in the case of the present wall plugs whether the fibrous material mass is held and stiffened inside or outside its circumference by one or 15 more straight or bent bars, wires or the like. In the former case the stiffening members are arranged within the body of the fibrous material near the outer surface thereof so that in this case also the greater portion of 20 the fibrous material is clamped by the stiffening bars or wires.

The cost of the stiffening bars is quite small, as they can be made from waste sheet metal, and at the same time the cost involved in the special shaping of sockets is 25 eliminated.

With wall plugs according to the present invention the holding power is considerably increased as compared with that of the ordinary known fibrous material sockets, whilst 30 their safety and reliability is also greatly improved. When employing the improved wall plugs it is only necessary to make a very small bore hole in the material into which 35 the plug is to be inserted, whilst at the same time the plugs have a very strong holding power, so that the present plugs present an advantage over other types of plug in this respect.

40 In order that the said invention may be clearly understood and readily carried into effect, the same will now be described more fully with reference to the accompanying drawings, in which:—

45 Figure 1 illustrates a wall plug in side elevation before the "stemming" or compression of the fibrous material therein.

Figure 2 shows the same wall plug viewed at an angle to Fig. 1 and in the hole of a 50 wall, in section, after wedging it in.

Figure 3 also shows the same wall plug as in Figure 1 in side elevation but with a nail driven in and in the condition it assumes in the wedged-in position.

55 Figure 4 represents a wall plug similar to that shown in Figure 1 but of a construction modified so as to assist a dove-tail-like spreading out of the strengthening bars.

Figure 5 represents the wall plug shown 60 in Figure 4, but in the condition it assumes in the wedged-in position.

Figure 6 is a detail view of a covering cap for the plug, and

65 Figure 7 a plug provided with a covering cap similar to that shown in Figure 6.

Referring to Figure 1, *a* is the fibrous material insertion which is pressed in between the stiffening bars *b* arranged outside the said material. These bars are bent into a *U* shape at *c* and formed into fingers at *d* 70 at which point is located a holding collar *k*.

In Figure 2, *e* is the deep hole in the portion of wall *f* shown in section. By striking against the end *d* of the bars, the plug is first driven into the wall until the collar 75 *k* rests against the face of the wall. In driving a nail or a screw into the fibrous material *a*, the latter is compressed in the axial direction between the bars *b* and forcibly stemmed at the end *c* of the plug. The 80 fibrous material then overflows laterally from the bars and presses firmly, with production of a frictional pressure, against the walls of the hole, the bars *b* being simultaneously bulged out and held fast in the dove-tail-like wedge position as indicated in a 85 somewhat exaggerated manner for the sake of clearness in Figure 3.

On considering the pressures exercised by the fibrous material insertion *a* on the bars, 90 it will be seen that the fingers *d* and collar *k* are subjected not only to radial pressure and are firmly held by friction, but are also subjected to the axial pressure of the said insertions whereby the said fingers *d* and 95 collar *k* are firmly fixed. The hard hammer blow on the nail is elastically taken up by the fibrous material and transmitted to the fingers *d* and collar *k* so that the soft 100 plaster is not overstrained by the blow, thus porcelain parts for instance may be safely secured, as by means of a drive screw, without any risk of breaking them by hammer blows.

The plugs according to the present invention can be used when driven in to serve as holding members either by means of a driven-in nail or screw or without the use of such nail or screw. In this latter case, 105 that is when the plug is used to fix a member to a wall or the like without the use of a nail or screw, the hole into which the plug is driven should be made of less depth than the length of the plug, so that on driving in the plug the bars *b* are bulged out similarly to what takes place when a nail is used 110 as shown in Figure 3 and some of the fibrous material overflows laterally from the bars and presses against the walls of the hole. When the parts fixed by the collar shrink 115 and warp, the plug can be tightened up by a hammer blow on the fibrous material mass, as owing to the blow, the arc *c* is first elastically compressed until the collar (or fingers) 120 has again obtained a firm hold, whilst the bars will be held fast elastically in the new position under compression by the frictional pressure of the mass of fibrous material, some of which has been pushed to the side 125 and forced out when the plug was first 130

driven in. It will be seen therefore that when the plug is provided with a collar or fingers and when it is used in the manner just described, it can be employed in place of an ordinary screw or nail for holding two members together. The time necessary for driving in a screw is therefore saved as the plug may be driven in place to hold the members together by a hammer blow.

10 It will be seen that a forcibly applied dove-tail-like wedging of the plug is rendered possible only by means of the present invention which involves the joint use of the fingers or bar hold *d*, the "stem" hold *c* and the resilient filling mass *a*.

If for instance the fingers *d* were omitted, the stiffening bars would slide, together with the fibrous material, right down to the bottom of the hole in the wall. The efficacy of 20 the plug would not then be a fixed factor, but would depend on the depth of the hole and would be practically indeterminable. On the other hand, without the "stem" hold *c* for the fibrous material, the latter would 25 slide between the bars secured to the ring, down to the bottom of the hole, and press uselessly against the deeper portion of the bottom of the hole and of the walls. Even with a suitable depth of hole, the bars would 30 then be held only by lateral pressure, and the axial pressure of the fibrous material plug would act uselessly on the bottom of the hole.

By the counter-bending of the bars *b* as 35 shown at *h* in Figure 4, the dove-tail-like spreading out of the bars *b* is assisted as shown in Figure 5.

Here also, in driving in a nail or the like 40 into the fibrous material, the plug is first resiliently driven in until the collar *k* is firmly fixed, and then the contracting fibrous material mass *a*, owing to the increasing pressure during its stemming and compressions, flattens out the counter bent *h*, where- 45 by teeth, rough edges or the like which may sion, flattens out the counter bent *h*, where- be formed on the bars *b* penetrate into the walls of the hole and firmly secure the plug proper after the fixing.

50 Instead of the collar shown in Figures 1 to 5, there may be employed an arrangement as shown in Figures 6 and 7, in which a bent-over sheet metal plate *l* with a central aperture *m* is used to cover the end of the plug. It is preferred in such case to make 55 the hole in the plate irregular in shape as shown in Fig. 6 so that the resulting teeth of the hole can engage on the one hand with the thread of a screw, and on the other hand 60 accommodate the different thicknesses of nails and therefore give the latter a good

hold where they are driven in and at the same time prevent the escape of the mass of fibrous material. In this connection it will be noted that the above mentioned teeth will 65 bend back as a nail is driven in and the amount of such bending will depend upon the size of the nail, there being more of such bending for larger nails and less for smaller ones.

70 As shown in Figure 7, this covering cap can also be used in combination with the collar, owing to which the strength of the holding disc is materially increased.

What I claim and desire to secure by Letters Patent of the United States is:—

1. A wall plug comprising a filling material, and stiffening members arranged so as to form a framework open at the sides and one end, said filling material being held 80 between and stiffened by said stiffening members and said stiffening members being connected together by a transverse portion at one end so as to form a stem-hold for the filling material and provided at the other 85 end with retaining means adapted to hold the plug in position when in use.

2. A wall plug comprising a fibrous filling material and stiffening members arranged so as to form a framework open at the sides and one end, said filling material being held between and stiffened by said stiffening members, and said stiffening members being connected together by a transverse portion at one end so as to form a stem-hold for the 90 filling material and provided at the other end with retaining means adapted to hold the plug in position when in use.

3. A wall plug comprising a fibrous filling material and an approximately U shaped 100 stiffening member between the legs of which the fibrous material is squeezed, said stiffening member being provided at its open end with retaining members adapted to hold the plug in position when in use.

4. A wall plug as claimed in claim 3 in which the U shaped stiffening member is provided at its open end with fingers and a holding collar for the purpose specified.

5. A wall plug as claimed in claim 3, in 110 which the closed end of the stiffening member is formed into a U shaped counterbend or arc for the purpose specified.

6. A wall plug comprising a fibrous filling material and an approximately U shaped 115 stiffening member between the legs of which the fibrous material is squeezed, said stiffening member having its closed end formed into a U shaped counterbend or arc and being provided at its open end with fingers and a holding collar.

FRIEDRICH WALTER KRAUSE.
